Specification of Letters Patent. Patented Mar. 30, 1915.

Application filed January 5, 1915. Serial No. 577.

To all whom it may concern:

Be it known that I, BERNARD COURLAENDER, Jr., a citizen of the United States, residing at Philadelphia, in the State of Pennsylvania, have invented a certain new and useful Improvement in Horseshoes, whereof the following is a specification, reference being had to the accompanying drawing.

10 My invention may be employed with particular advantage in the construction of horseshoes which may be drop forged or cast or otherwise be ready made, by successive casting and forging processes so as to minimize the amount of farrier work required to fit and apply them.

15 It is the object of my invention to provide a horseshoe with means to prevent slipping thereof, so constructed and arranged as to afford an auxiliary wearing surface at the regions of the shoe which are subjected to the most attrition.

20 As hereinafter described, my invention provides a horseshoe with a toe calk forming a continuous annular frame around a recess adapted to receive and hold grit from the road; thus affording a frictional bearing surface within said frame. I found in practice that such hollow calks were worn away 25 in two places to a greater extent than elsewhere, to wit, at the front on the medial line of the shoe and also at the side of the front of the calk which is given a rolling scraping movement by the action of the horse.

30 Therefore, I provide such a hollow calk with an auxiliary wearing surface on the medial line of the shoe extending inwardly from the inner margin of said frame so as to afford a wearing surface at that region

35 approximately double the width, from front to rear, of the other portions of the front of said frame, and extend said frame laterally upon the side which is subjected to the rolling action so as to not only afford a wearing

40 surface there approximately double the width of the narrower portions of the frame but project said lateral surface laterally beyond the normal contour of the shoe so as to bring such lateral wearing surface in longitudinal alinement with a calk upon the heel of the shoe at that side; the opposite heel of the shoe being also provided with a calk, but the latter being out of longitudinal alinement with the edge of the front calk

upon that side so as to give the shoe a tendency to roll upon that side which is opposite to the side which is caused to roll by the action of the horse; so that, in the most complex form of my invention, the tendency to maximum wear upon one side of the toe of the shoe is counteracted both by the construction and arrangement of the toe calk and by the construction and arrangement of the heel calks in coöperative relation therewith.

45 My invention includes the various novel features of construction and arrangement hereinafter more definitely specified.

50 In the drawing; Figure I is an inverted plan view of a horseshoe embodying my invention. Fig. II is a rear elevation of said shoe. Fig. III is a central sectional view of said shoe taken on the line III, III in Fig. I.

55 In said figures; the horseshoe 1 is provided with fullering 2 and nail holes 3 in its quarters and has at its toe the hollow calk 5 extending as a continuous frame around the recess 6 which acts as a receptacle for grit from the road, affording a surface with a greater coefficient of friction than the metal surface of said calk. Said calk is reinforced at the front edge of its frame, at the medial longitudinal line 8, by the projection 9 extending inwardly with 60 respect to said recess 6 and affording approximately double the width of wearing surface afforded by the adjoining front portions of said frame; such proportions being 65 determined by the fact that it is desirable to have said recess 6 of the greatest area possible with the continued maintenance of the calk frame surrounding it during the wear 70 to which the shoe is subjected by use. Said hollow calk 5 is also extended laterally at 75 11 so as to project beyond the normal configuration of the shoe indicated by the dotted line 12, at that side of the shoe toe 80 which is subjected to rolling attrition by the action of the horse; and said calk is also 85 extended longitudinally at said side, as indicated at 14, so as to afford an auxiliary wearing surface at that side, of approximately 90 double the width of the adjoining portions of the calk frame. The heels 15 and 16 of said shoe are respectively provided with calks 18 and 19, preferably 95 pointed both at their front and rear ends 100 105

and at their sides to afford cutting edges to engage ice and prevent slipping of the shoe either longitudinally or laterally. It may be observed that said calk 18 is placed in longitudinal alinement with said lateral wearing surface 11, 14 and that said calk 19 is placed out of longitudinal alinement with the edge of the front calk 5 upon that side, so as to give the shoe a tendency to roll 10 upon that side which is opposite to the side which is caused to roll by the action of the horse, while affording additional support tending to prevent the latter rolling action. It may be observed that if either of the 15 calks 18 or 19 were omitted there would be a greater freedom for the shoe to respond to the rolling action of the horse, and that the greatest maximum of distance to such action is afforded by the described action of 20 the heel calks in coöperative relation with the toe calk.

Although I prefer to form the heel calks with the rhombic configuration shown; it is to be understood that they may be otherwise 25 shaped, for instance, either or both of them may be formed with a recess to receive and hold grit from the road, like the toe calk. Moreover, although I have shown a shoe with an auxiliary projection of the toe calk 30 toward the left hand side thereof, when the shoe is in wearing position, it is, of course, to be understood that shoes may be provided with such projections toward either side.

I do not desire to limit myself to the precise details of construction and arrangement 35 of my invention herein set forth, as it is obvious that various modifications may be made therein without departing from the essential features thereof as defined in the 40 appended claims.

I claim:—

1. In a horseshoe, the combination with a 45 toe calk forming a continuous annular frame around a recess adapted to receive and hold grit from the road, and having an auxiliary wearing surface on the medial line of the shoe extending inwardly from the inner margin of said frame, in said recess, affording a wearing surface at that region approx- 50 imately double the width, from front to rear, of the other portions of the front of said frame, and having an auxiliary wearing surface of said frame extending laterally upon one side thereof so as to afford a wearing surface, at that side, approximately 55 double the width of the narrower portions of the frame and projecting laterally beyond the normal contour of the shoe; of a calk 60 upon the heel of the shoe, at that side, in longitudinal alinement with said lateral wearing surface; and a calk upon the opposite heel of the shoe; the latter calk being out of longitudinal alinement with the edge 65 of the front calk upon that side; whereby the shoe has a tendency to roll upon that

side of the toe opposite to the side which is caused to roll by the action of the horse, so that the tendency to maximum wear upon one side of the toe of the shoe, by the rolling action of the horse, is counteracted both by 70 the construction and arrangement of the toe calk and by the construction and arrangement of the heel calks in coöperative relation therewith.

2. In a horseshoe, the combination with a 75 toe calk forming a continuous annular frame around a recess adapted to receive and hold grit from the road, and having an auxiliary wearing surface on the medial line of the shoe extending inwardly from the inner 80 margin of said frame, in said recess, and having an auxiliary wearing surface of said frame extending laterally upon one side thereof projecting laterally beyond the normal contour of the shoe; of a calk upon the 85 heel of the shoe, at that side, in longitudinal alinement with said lateral wearing surface; and a calk upon the opposite heel of the shoe; the latter calk being out of longitudinal alinement with the edge of the front 90 calk upon that side; whereby the shoe has a tendency to roll upon that side of the toe opposite to the side which is caused to roll by the action of the horse, so that the tendency to maximum wear upon one side of the 95 toe of the shoe, by the rolling action of the horse, is counteracted both by the construction and arrangement of the toe calk and by the construction and arrangement of the heel calks in coöperative relation therewith. 100

3. In a horseshoe, the combination with a 105 toe calk forming a continuous annular frame around a recess adapted to receive and hold grit from the road, and having an auxiliary wearing surface on the medial line of the shoe extending inwardly from the inner margin of said frame, in said recess, and having an auxiliary wearing surface of said frame extending laterally upon one side thereof projecting laterally beyond the normal contour of the shoe; of a calk upon the 110 heel of the shoe, at that side, in longitudinal alinement with said lateral wearing surface; whereby the shoe has a tendency to roll upon that side of the toe opposite to the side which is caused to roll by the action of the horse, so that the tendency to maximum wear upon one side of the toe of the shoe, by the rolling action of the horse, is counteracted both by the construction and arrangement of the toe calk and by the construction and arrangement of the heel calk in coöperative relation 115 therewith. 120

4. In a horseshoe, the combination with a 125 toe calk forming a continuous annular frame around a recess adapted to receive and hold grit from the road, and having an auxiliary wearing surface on the medial line of the shoe extending inwardly from the inner margin of said frame, in said recess, and 130

- having an auxiliary wearing surface of said frame extending laterally upon one side thereof projecting laterally beyond the normal contour of the shoe; of a calk upon the 5 heel of the shoe, upon the side opposite said lateral projection; said heel calk being out of longitudinal alinement with the edge of the toe calk upon that side; whereby the shoe has a tendency to roll upon that side of the 10 toe opposite to the side which is caused to roll by the action of the horse, so that the tendency to maximum wear upon one side of the toe of the shoe, by the rolling action of the horse, is counteracted both by the 15 construction and arrangement of the toe calk and by the construction and arrangement of the heel calk in coöperative relation therewith.
5. In a horseshoe, the combination with a 20 toe calk forming a continuous annular frame around a recess adapted to receive and hold grit from the road, and having an auxiliary wearing surface on the medial line of the shoe extending inwardly from the inner 25 margin of said frame, in said recess, affording a wearing surface at that region approximately double the width, from front to rear, of the other portions of the front of said frame, and having an auxiliary wearing 30 surface of said frame extending laterally upon one side thereof so as to afford a wearing surface, at that side, approximately double the width of the narrower portions of the frame and projecting laterally beyond 35 the normal contour of the shoe.
6. A horseshoe having a toe calk forming a continuous annular frame around a recess adapted to receive and hold grit from the road, and having an auxiliary wearing 40 surface on the medial line of the shoe extending inwardly from the inner margin of said
- frame, in said recess, and having an auxiliary wearing surface of said frame extending laterally upon one side thereof projecting laterally beyond the normal contour of the 45 shoe.
7. A horseshoe having a toe calk forming a continuous annular frame around a recess adapted to receive and hold grit from the road, and having an auxiliary wearing surface on the medial line of the shoe extending 50 inwardly from the inner margin of said frame, in said recess, and having an auxiliary wearing surface of said frame extending laterally upon one side thereof. 55
8. A horseshoe having a toe calk forming a continuous annular frame around a recess adapted to receive and hold grit from the road, and having an auxiliary wearing surface on the medial line of the shoe extending 60 inwardly from the inner margin of said frame, in said recess.
9. A horseshoe having a projection upon one side of its toe, forming an auxiliary wearing surface extending laterally beyond 65 the normal contour of the shoe, and a recess in said toe, extending in said auxiliary wearing surface, adapted to receive and hold grit from the road.
10. A horseshoe having a recess in its 70 wearing surface, at its toe, adapted to receive and hold grit from the road and extending laterally more upon one side than the other of the longitudinal medial line of the shoe. 75

In testimony whereof, I have hereunto signed my name at Philadelphia, Pennsylvania, this thirtieth day of December, 1914.

BERNARD COURLAENDER, JR.
